The ornamental design for a dog feeder, as shown and described.

DESCRIPTION

FIG. 1 is a top plan view of a dog feeder showing my new design;

FIG. 2 is a bottom plan view thereof;

FIG. 3 is a right side elevational view thereof;

FIG. 4 is a left side elevational view thereof;

FIG. 5 is a front elevational view with the rear elevational view being a mirror image thereof; and,

FIG. 6 is a perspective view thereof.

The broken line showing of the wing nut and the bolt in FIGS. 2, 3, 4, and 6 is for illustrative purposes only, merely showing the types of attachments which can be used, and forms no part of the claimed design. The broken line showing of the bowls in FIGS. 3 and 4 is for illustrative purposes only and forms no part of the claimed design.
